HAND MIXER

Ralph Morris, St. Paul, Minn., assignor to Fingerhut
Manufacturing Company, Minneapolis, Minn.

Filed Feb. 8, 1971, Ser. No. 113,810

Term of patent 14 years

Int. Cl. D7—04

U.S. Cl. D44—1

FIG. 1 is a front side perspective view of a hand mixer embodying my new design;

FIG. 2 is a side elevational view thereof;

FIG. 3 is a top view thereof;

FIG. 4 is a front elevational view thereof;

FIG. 5 is a back elevational view thereof; and

FIG. 6 is a bottom view thereof.

I claim:

The ornamental design for a hand mixer, as shown.
